UNITED STATES PATENT OFFICE.

SAMUEL J. MATHEWS, OF SAPULPA, OKLAHOMA, ASSIGNOR TO B-B MANUFACTURING AND DRILLING COMPANY, A CORPORATION OF DELAWARE.

WELL-DRILLING APPARATUS.

Application filed April 9, 1920. Serial No. 372,397.

To all whom it may concern:

Be it known that I, SAMUEL J. MATHEWS, a citizen of the United States of America, residing at the city of Sapulpa, State of Oklahoma, United States of America, have invented a certain new and useful Well-Drilling Apparatus, of which the following is such a full, clear, and exact description as will enable anyone skilled in the art to which it appertains to make and use the same, reference being had to the accompanying drawings, forming part of this specification.

My invention relates to the type of well drilling apparatus illustrated in my prior Patent No. 1,077,620 issued Nov. 4, 1913, in which the tool is actuated by motors contained within a casing which is suspended in the well casing by a cable and permitted to descend as the drilling proceeds. In such apparatus it is important that water be kept on and moving over the surface being cut to promote cutting, reduce wear on the cutters, and carry away the abraded material. The cutters are directly driven by electric motors and rotate rapidly, that is to say from about one thousand to two thousand revolutions per minute and this rapid rotation has the effect of throwing upward the water which lies between the cutters and on the surface to be cut when the apparatus is at rest and preventing water from above from reaching the cutting surface in sufficient quantity for the proper wetting of this surface. My invention is directed to means for overcoming this difficulty.

In the accompanying drawings which illustrate one embodiment of my invention, Figure 1 is a side view showing a well casing, motor casing therein, and the bits or cutting tools all in position in the well. Figure 2 is an enlarged view partly in vertical section and partly in elevation of the lower portion of the apparatus illustrated in Figure 1. Figure 3 is a horizontal cross section along the line 3-3 of Figure 2. Figure 4 is a horizontal cross section along the line 4-4 of Figure 2 and Figure 5 is a bottom plan view of the tool holder and cutters shown in Figures 1 and 2.

1 represents the well casing which is lowered as the drilling proceeds in accordance with common practice and 2 represents a water tight casing within which is contained one or more electric motors (not shown)

which are supplied with current from the surface of the ground through conducting wires (not shown). The motor casing is supported by the cable 3 and from the lower end of the casing extends the motor shaft 4 to which is attached the cutting head comprising the tool holder 5, the pivoted wing bits or cutters 6, wing bits 7, and pilot bit 8. The bits are of abrasive material such as carborundum. Attached to the cutter head and surrounding the shaft 4 is a shell 9 which slidingly enters the extension 10 of the motor casing. This shell is connected to the cutter head to form a water tight joint and thus produces a water container surrounding the shaft 4 into which water enters from the well casing through opening 11 in the extension of the motor casing and from which it can only emerge through openings 12 in the outer periphery of the cutter head and passages 15 formed on either side of the pilot bit connecting with vertical passage 14 in the cutter head which in turn communicates with horizontal passages 13 in the head. Within the shell and either attached thereto or to the shaft 4 is an impeller 16 provided with blades 17 so positioned with respect to the direction of motion of the shaft and shell as to impel the contained water downwardly and in addition to the impeller 16 obliquely positioned propeller blades 18 are positioned adjacent to the upper ends of the openings 12 in the tool holder and curved impeller blades 19 are positioned adjacent the ends of the horizontal passages 13 in the tool holder. For the purpose of restricting flow of water between the outer surface of the shell and the interior of the well casing 1, a packing ring 20 is positioned around the shell.

The operation of the apparatus described is substantially as follows: The hole as it is being drilled is kept full of water which is supplied to the interior of the well casing. The rotation of the cutting head and associated parts including the impelling blades applies a downward pressure to the water contained within the shell 9 and assists in initiating and maintaining a circulation of water downward through the openings in the cutter head and to the surface to be cut.

The peripheral speed of the pilot bit is not sufficient to prevent water from reaching the cutting surface operated upon by this bit and the water being supplied to the area

between bits 7 is confined between the bits and the lower surface of the cutting head so that the effect of the centrifugal force caused by the motion of the water produced by the bits must be to drive the water outwardly and under pressure over the surface operated upon by bits 7 and then to the surface operated upon by bits 6. The relatively great peripheral speed of these bits causes the water to be discharged outwardly and upwardly and tends to create a vacuum beneath the tool holder and thus rapid circulation of the water through the tool holder and over the surfaces to be cut is promoted, both sets of bits 6 and 7 and the impellers 16, 18, and 19 contributing to this result. The circulation of the water passing the bit 6 is upward and out of the well through the space between the well casing 1 and the inner surface of the opening cut by the cutter 6, this cutter being larger than the well casing and being pivotally supported to permit withdrawal of the motor casing and cutter head from the well through the well casing.

Having fully described my invention, what I claim as new and desire to secure by Letters Patent of the United States is:

1. In apparatus of the class described, the combination of a well casing, a cutting tool, means forming a water container communicating with the interior of the well casing and discharging adjacent the cutting tool, and means preventing reentrance of discharged water into the well casing.

2. In apparatus of the class described, a cutting head comprising a cutting tool, a tool holder and driving member therefor, said head being provided with spaced peripheral openings for the passage of water from its upper to its lower surface, said openings being inclined to the plane of the axis of rotation of the head.

3. In apparatus of the class described, the combination of a cutting head carrying a plurality of radially extending spaced cut-

ting tools, and means providing a water passage downward through the central portion of the head, the size and position of the cutting tools with respect to the head being such as to provide a confined space for the passage of water between the tools and between the lower surface of the head and the surface to be cut whereby water passing downward through the head and actuated by the tools is forced to pass over the surface to be cut.

4. In well drilling apparatus the combination of a well casing, a motor casing within the well casing and provided with a downward extension, a driving shaft in said motor casing and extending downward beyond the extension of the motor casing, a cutter head provided with water passages therethrough and mounted on said shaft, a shell surrounding said cutter head and shaft and slidably fitting into the extension of the motor casing, a packing ring surrounding the shell to substantially close the space between the shell and the well casing, and means forming a water passage connecting the interior of the well casing with the interior of the shell.

5. In well drilling apparatus the combination of a well casing, a motor casing within the well casing and provided with a downward extension, a driving shaft in said motor casing and extending downward beyond the extension of the motor casing, a cutter head provided with water passages therethrough and mounted on said shaft, a shell surrounding said cutter head and shaft and slidably fitting into the extension of the motor casing, a packing ring surrounding the shell to substantially close the space between the shell and the well casing, and means within the shell for applying downward pressure to water contained therein.

In testimony whereof, I have hereunto set my hand and affixed my seal.

SAMUEL J. MATHEWS. [L.S.]
